FORMATION OF NONLINEAR DIELECTRIC FILMS FOR ELECTRICALLY TUNABLE MICROWAVE DEVICES

FIELD OF THE INVENTION

The present invention relates to electrically tunable devices based on nonlinear dielectric SrTiO_3 , and more particularly to electrically tunable devices based on nonlinear dielectric SrTiO_3 using a homoepitaxial interlayer between the substrate and the dielectric film. This invention was made with government support under Contract No. W-7405-ENG-36 awarded by the U.S. Department of Energy. The government has certain rights in the invention.

BACKGROUND OF THE INVENTION

Electrically tunable microwave devices based on a $\text{YBa}_2\text{Cu}_3\text{O}_{7-x}/\text{SrTiO}_3$ multilayer have been extensively investigated. In those designs, advantage is taken of the dc electric field tunability of a nonlinear dielectric SrTiO_3 film and the very low conductor losses in high-temperature superconducting $\text{YBa}_2\text{Cu}_3\text{O}_{7-x}$ (YBCO) electrodes at cryogenic temperatures below 90 K. For practical dc electric-field tunable microwave devices such as voltage-tunable resonators and voltage-tunable filters, it is desirable to grow high-quality dielectric SrTiO_3 thin films that have as large a dielectric tunability and as low dielectric losses as possible. Unfortunately, previous studies have shown that the effective loss tangent from a generic YBCO/ SrTiO_3 multilayer is on the order of 10^{-2} which is much higher than a value of 10^{-4} observed in a single-crystal SrTiO_3 .

Others have made efforts to look for new nonlinear dielectric materials and to use different dopants such as calcium and/or zinc in SrTiO_3 to reduce the loss tangent.

It has been shown that dielectric losses in SrTiO_3 film play the most important role in determining the performance of microwave devices. These dielectric losses include losses in the bulk of the SrTiO_3 film, the losses at the interface between the substrate and the SrTiO_3 film, and the losses at the interface between the SrTiO_3 film and the YBCO electrode.

Thus, one object of the present invention is to improve the microstructural properties of SrTiO_3 films so as to enhance the microwave properties of devices based on a YBCO/ SrTiO_3 multilayer.

Another object of the present invention is to provide a thin homoepitaxial LaAlO_3 interlayer between a LaAlO_3 substrate and a SrTiO_3 film to reduce the defect density in the SrTiO_3 film.

Still another object of the present invention is to provide a coplanar waveguide device structure including SrTiO_3 as a nonlinear dielectric and superconducting YBCO as an electrode.

Yet another object of the present invention is to use a thin homoepitaxial LaAlO_3 interlayer between a LaAlO_3 substrate and a YBCO film.

SUMMARY OF THE INVENTION

To achieve the foregoing and other objects, and in accordance with the purposes of the present invention, as embodied and broadly described herein, the present invention provides a thin film structure including a lanthanum aluminum oxide substrate, a thin layer of homoepitaxial lanthanum aluminum oxide thereon, and a layer of a nonlinear dielectric material thereon the thin layer of homoepitaxial lanthanum aluminum oxide.

2

The present invention also provides a thin film structure including a lanthanum aluminum oxide substrate, a thin layer of homoepitaxial lanthanum aluminum oxide thereon, and a layer of superconducting material thereon the thin layer of homoepitaxial lanthanum aluminum oxide.

The present invention also provides a method of making an improved microwave device by use of a thin layer of homoepitaxial lanthanum aluminum oxide situated directly between a lanthanum aluminum oxide substrate and a layer of nonlinear dielectric material, followed by a layer of superconducting material on the layer of nonlinear dielectric material.

BRIEF DESCRIPTION OF THE DRAWINGS

FIG. 1 shows a coplanar waveguide structure as constructed in the present invention.

FIG. 2 shows the quality factor for a standing wave resonance at a microwave frequency of about 4.2 gigahertz (GHz) and at a temperature of 4 K, measured as a function of dc bias applied between the centerline and the ground-plates.

FIG. 3 shows the finesse factor at 4.2 GHz and 4 K as a function of dc bias for the voltage-tunable coplanar waveguide microwave resonators made from identically deposited YBCO/ SrTiO_3 bilayers with and without a homoepitaxial LaAlO_3 interlayer on LaAlO_3 substrates.

DETAILED DESCRIPTION

The present invention is concerned with use of a homoepitaxial layer of a material such as LaAlO_3 on an underlying base substrate of the same material (i.e., LaAlO_3) to improve the properties of a multilayer structure including the underlying base substrate, the layer of the homoepitaxial material, and a subsequently deposited material of a different material than the underlying base substrate or layer of homoepitaxial material. The different material can be, e.g., a nonlinear dielectric material or a high temperature superconducting material. The present invention is also concerned with microwave devices employing such a multilayer structure. Such a microwave device can include a nonlinear dielectric material in combination with a high temperature superconducting material for a low temperature device. Similarly, such a microwave device may include a nonlinear dielectric material in combination, preferably with a conductive metal oxide as a buffer layer between the dielectric material and the contact electrodes, for a room temperature device. The present invention is also concerned with electro-optical devices employing such a multilayer structure of the same material.

The nonlinear dielectric material in the present invention can be strontium titanate (SrTiO_3), barium titanate (BaTiO_3), or can be a mixed titanate such as barium-strontium titanate ($\text{Ba}_x\text{Sr}_{1-x}\text{TiO}_3$ often referred to as BSTO). Other nonlinear dielectric materials such as $\text{PbZr}_x\text{Ti}_{1-x}\text{O}_3$ (PZT), LiNbO_3 , LiTaO_3 , La-modified PZT, and doped-BSTO (doping, e.g., with tungsten, magnesium oxide, calcium or zinc) may be used as well.

The underlying base substrate in the present invention can be lanthanum aluminum oxide (LaAlO_3), e.g., a single crystal LaAlO_3 substrate, or may be other materials such as MgO , NdGaO_3 , $\text{Sr}_2\text{AlTaO}_6$, or $(\text{LaAlO}_3)_{0.3}(\text{Sr}_2\text{AlTaO}_6)_{0.7}$. The homoepitaxial layer upon the substrate is then of the same material as the substrate. Preferably, the base substrate is a LaAlO_3 substrate and the homoepitaxial layer is of LaAlO_3 .

The high temperature superconducting material in the present invention can be any of the conventionally recognized materials such as yttrium barium copper oxide ($\text{YBa}_2\text{Cu}_3\text{O}_7$ or YBCO), or yttrium barium copper oxide substituted with a minor amount of an additional cation such as silver and the like. Generally such a minor amount will be up to about 10 percent by weight, more preferably from about 3 to about 7 weight percent. Other superconducting materials such as $\text{GdBa}_2\text{Cu}_3\text{O}_7$, $\text{NdBa}_2\text{Cu}_3\text{O}_7$, $\text{SmBa}_2\text{Cu}_3\text{O}_7$, $\text{YbBa}_2\text{Cu}_3\text{O}_7$, $\text{ErBa}_2\text{Cu}_3\text{O}_7$, may be used as well.

Conductive metallic oxides can be used as buffer layers between the dielectric material and metallic contact electrodes for room temperature devices in accordance with the present invention. The conductive metallic oxides can be of materials such as lanthanum strontium cobalt oxide (LSCO), strontium ruthenium oxide (SRO), ruthenium oxides (RuO_x), lanthanum strontium chromium oxide and the like.

The various material layers can be deposited by pulsed laser deposition or by other well known methods such as evaporation, sputtering, or chemical vapor deposition. Pulsed laser deposition is the preferred deposition method.

In pulsed laser deposition, powder of the desired material, e.g., LaAlO_3 can be initially pressed into a disk or pellet under high pressure, generally above about 500 pounds per square inch (PSI) and the pressed disk then sintered in an oxygen-containing atmosphere for at least about one hour, preferably from about 12 to 24 hours. An apparatus suitable for the pulsed laser deposition is shown in Appl. Phys. Lett., 56, 578(1990), "effects of beam parameters on excimer laser deposition of $\text{YBa}_2\text{Cu}_3\text{O}_{7-x}$ ", such description hereby incorporated by reference.

Suitable conditions for pulsed laser deposition include, e.g., the laser, such as a XeCl excimer laser (20 nanoseconds (ns), 308 nanometers (nm)), targeted upon a rotating pellet of the desired material at an incident angle of about 45°. The target substrate can be mounted upon a heated holder rotated at about 0.5 revolutions per minute (rpm) to minimize thickness variations in the resultant film or layer. The substrate can be heated during the deposition at temperatures from about 600° C. to about 950° C., preferably from about 700° C. to about 850° C. An oxygen atmosphere of from about 0.1 millitorr (mTorr) to about 10 Torr, preferably from about 100 mTorr to about 250 mTorr, can be maintained within the deposition chamber during the deposition. Distance between the substrate holder and the pellet can generally be from about 4 centimeters (cm) to about 10 cm.

The rate of formation of the thin films or layers can be varied from about 0.1 Angstrom per second ($\text{\AA/s}$) to about 200 $\text{\AA/s}$ by changing the laser repetition rate from about 1 hertz (Hz) to about 200 Hz. As laser beam divergence is a function of the repetition rate, the beam profile can be monitored after any change in repetition rate and the lens focal distance adjusted to maintain a constant laser energy density upon the target pellet. Generally, the laser beam can have dimensions of about 3 millimeters (mm) by 4 mm with an average energy density of from about 1 to about 5 joules per square centimeter (J/cm^2), preferably from about 1.5 to about 3 J/cm^2 .

The present invention is more particularly described in the following examples, which are intended as illustrative only, since numerous modifications and variations will be apparent to those skilled in the art.

EXAMPLE 1

YBCO/ SrTiO_3 multilayer structures with and without a homoepitaxial LaAlO_3 interlayer were deposited on LaAlO_3

substrates (100 orientation) by in situ pulsed laser deposition (PLD) using a 308 nm XeCl excimer laser. The homoepitaxial LaAlO_3 interlayer was grown on the LaAlO_3 substrates at temperatures from about 650° C. to about 785° C. with an oxygen pressure of about 200 milliTorr (mTorr). The LaAlO_3 interlayer had a thickness of from about 2 nanometers (nm) to about 25 nm. Following the growth of the homoepitaxial LaAlO_3 interlayer, the SrTiO_3 layer was deposited by switching the target without breaking vacuum on the deposition system. The deposition temperature for the SrTiO_3 layer was initially optimized and then maintained at 785° C. The thickness of the SrTiO_3 films was varied from about 0.4 microns (μm) to about 1.0 μm . A superconducting YBCO layer with a thickness of about 0.4 μm was then deposited at a substrate temperature of 775° C. The superconducting transition temperature of the YBCO on SrTiO_3 films with and without a homoepitaxial LaAlO_3 interlayer on LaAlO_3 substrates was above 88 K with a transition width of less than 0.6 K.

The microstructure of SrTiO_3 thin films on LaAlO_3 substrates with and without a homoepitaxial LaAlO_3 interlayer was examined by transmission electron microscopy (TEM) and high resolution electron microscopy (HREM) in cross-section in the [100] direction. Cross-sectional TEM micrographs of the SrTiO_3 thin films on LaAlO_3 substrates with and without a homoepitaxial LaAlO_3 interlayer revealed the following. Antiphase boundaries, characterized by a contrast fluctuation across such boundaries, often initiated at the interface between the SrTiO_3 thin film and the LaAlO_3 substrate (or interlayer) and extended to the SrTiO_3 film surface. HREM observation on these defects indicated that most of the boundaries had a projected displacement across the boundaries of $\frac{1}{2}\langle 110 \rangle$. Similar boundaries were previously found in various epitaxially grown perovskite thin films such as YBCO, BaTiO_3 and KNbO_3 . While not wishing to be bound by the present explanation, it is believed that these boundaries could be formed as a result of non-perfect epitaxial growth. To make a qualitative comparison between the SrTiO_3 thin films on LaAlO_3 substrates with and without a homoepitaxial LaAlO_3 interlayer, the density of the planar defects present in the SrTiO_3 films was calculated. The calculation was done by counting the number of planar defects in the direction along the interface and dividing the number by the distance. Areas having similar thicknesses were used for analysis in order to reduce the possible projection effect. The results from several different areas over a distance of a few microns were averaged. The defect density was about 20 per micron for SrTiO_3 thin films on LaAlO_3 substrates with a homoepitaxial LaAlO_3 interlayer and about 50 per micron for SrTiO_3 thin films on LaAlO_3 substrates without a homoepitaxial LaAlO_3 interlayer. Similar results were observed for other samples with different homoepitaxial LaAlO_3 interlayers and SrTiO_3 thicknesses.

The HREM examination had found that the homoepitaxial LaAlO_3 interlayer had many more structural defects than either the single crystal LaAlO_3 substrate or the SrTiO_3 film grown on top. A cross sectional HREM micrograph of a SrTiO_3 thin film on a LaAlO_3 substrate with about a 25 nm thick homoepitaxial LaAlO_3 interlayer showed that the SrTiO_3 film had about the same value of planar defect density as the film examined by TEM. A number of structural defects, mainly planar defects, were visible in the homoepitaxial LaAlO_3 interlayer. The planar defect density in the homoepitaxial LaAlO_3 interlayer was about 10 times higher than that of the SrTiO_3 layer deposited on top. Most of the planar defects present in the LaAlO_3 interlayer were found to be terminated near the homoepitaxial LaAlO_3 interlayer and the SrTiO_3 film interface.

To assess the microwave losses of the epitaxial SrTiO_3 films with and without a homoepitaxial LaAlO_3 interlayer, a coplanar waveguide structure as shown in FIG. 1 was fabricated incorporating a 1 micron thick SrTiO_3 layer and a 0.4 micron thick superconducting YBCO electrode. The top YBCO layer was patterned by wet chemical etching. Gold contact pads (0.2 micron thick) were deposited on YBCO by rf sputtering and patterned by a lift-off technique. The finished devices were annealed at 450° C. in oxygen. The device had a centerline width of 20 microns and a gap width of 40 microns between the centerline and the ground-plates. The device was designed and operated in the manner of the electrically tunable coplanar transmission line resonator as described by Findikoglu et al., *Appl. Phys. Lett.*, vol. 66, pp. 3674-3676 (1995), wherein YBCO/STO bilayers were grown directly on [001] LaAlO_3 substrates, such details incorporated herein by reference.

FIG. 2 shows the quality factor for a standing-wave resonance at a microwave frequency of about 4.2 gigahertz (GHz) and at a temperature of 4 K, measured as a function of dc bias applied between the centerline and the ground-plates. For a given voltage bias, the electric field amplitude decreases from the SrTiO_3 film surface to its interface with the substrate. Thus, the surface dc electric field used in the plot corresponds to the highest electric field in the SrTiO_3 film. As seen in FIG. 2, the quality factor of a YBCO/ SrTiO_3 multilayer device using a homoepitaxial LaAlO_3 interlayer was improved by more than 50 percent at a surface electric field of 3×10^4 volts per centimeter (V/cm) in comparison to a conventional device without such an interlayer.

Since the use of a homoepitaxial LaAlO_3 interlayer did not lead to any degradation in the dielectric tunability, the finesse factor had also improved by more than 50 percent for the same set of devices. FIG. 3 shows the finesse factor at 4.2 GHz and 4 K as a function of dc bias for the voltage-tunable coplanar waveguide microwave resonators made from identically deposited YBCO/ SrTiO_3 bilayers with and without a homoepitaxial LaAlO_3 interlayer on LaAlO_3 substrates. Examination of the data in both FIG. 2 and FIG. 3 indicates that this approach provides a way to enhance the quality factor without sacrificing the dielectric tunability of the SrTiO_3 films. Reduction of the defect density in the epitaxial SrTiO_3 films by use of such a homoepitaxial LaAlO_3 interlayer can lead to improvement on the device performance at 4 K since the losses at very low temperatures are more likely to be dominated by the defects in SrTiO_3 films. Such epitaxial SrTiO_3 films show more single-crystal like properties as evident from a temperature dependent quality factor and dielectric tunability.

The present results demonstrate that introduction of a homoepitaxial LaAlO_3 interlayer between a nonlinear dielectric SrTiO_3 film and a LaAlO_3 substrate can achieve more than a two-fold reduction in areal defect density in SrTiO_3 thin films. The reduction of planar defect density in SrTiO_3 thin films is accompanied by reduction in microwave losses. Coplanar waveguide microwave resonators have been fabricated based on a multilayer structure of YBCO/ SrTiO_3 / LaAlO_3 substrates. Enhancement of finesse factor by 50 percent has been observed by incorporation of the homoepitaxial LaAlO_3 interlayer between a nonlinear dielectric SrTiO_3 film and a LaAlO_3 substrate.

EXAMPLE 2

A thin layer of YBCO (doped with 7 percent Ag) was deposited on LaAlO_3 substrates (100 orientation) by in situ pulsed laser deposition (PLD) using a 308 nm XeCl excimer laser with and without a homoepitaxial LaAlO_3 interlayer. The homoepitaxial LaAlO_3 interlayer was grown on the LaAlO_3 substrates at temperatures from about 650° C. to about 785° C. with an oxygen pressure of about 200 milli-

Torr (mTorr). The LaAlO_3 interlayer had a thickness of from about 2 nanometers (nm) to about 25 nm. Following the growth of homoepitaxial LaAlO_3 interlayer, the YBCO layer was deposited by switching the target without breaking vacuum on the deposition system. The deposition temperature for the YBCO layer was optimized and then maintained at 780° C. The thickness of the YBCO films varied from about 0.2 microns (μm) to about 0.6 μm . The superconducting transition temperature of the YBCO with a homoepitaxial LaAlO_3 interlayer on LaAlO_3 substrates was above 88 K with a transition width of less than 0.5 K. The superconducting YBCO thin films exhibited a critical current density over 10^6 amperes per square centimeter (A/cm^2) at liquid nitrogen temperature.

Although the present invention has been described with reference to specific details, it is not intended that such details should be regarded as limitations upon the scope of the invention, except as and to the extent that they are included in the accompanying claims.

What is claimed is:

1. A thin film structure comprising a lanthanum aluminum oxide substrate, a thin layer of homoepitaxial lanthanum aluminum oxide thereon, and a layer of a nonlinear dielectric material thereon said thin layer of homoepitaxial lanthanum aluminum oxide.
2. The structure of claim 1 wherein said nonlinear dielectric material is selected from the group consisting of strontium titanium oxide, barium strontium titanium oxide and barium titanium oxide.
3. The structure of claim 1 wherein said nonlinear dielectric material is strontium titanium oxide.
4. The structure of claim 1 wherein said nonlinear dielectric material is barium titanium oxide.
5. The structure of claim 1 wherein said nonlinear dielectric material is barium strontium titanium oxide.
6. The structure of claim 1 further including a layer of high temperature superconducting material on the layer of nonlinear dielectric material.
7. The structure of claim 6 wherein said high temperature superconducting material is yttrium barium copper oxide.
8. The structure of claim 1 further including a layer of an electrode material on the layer of nonlinear dielectric material and a buffer layer between the layer of nonlinear dielectric material and the layer of electrode material.
9. The structure of claim 8 wherein said buffer layer is selected from the group consisting of lanthanum strontium cobalt oxide, strontium ruthenium oxide, and ruthenium oxides.
10. A thin film structure comprising a lanthanum aluminum oxide substrate, a thin layer of homoepitaxial lanthanum aluminum oxide thereon, and a layer of superconducting material thereon said thin layer of homoepitaxial lanthanum aluminum oxide.
11. The structure of claim 10 wherein said superconducting material is yttrium barium copper oxide.
12. A method of making a microwave device comprising: forming a thin layer of homoepitaxial lanthanum aluminum oxide situated directly between a lanthanum aluminum oxide substrate and a layer of nonlinear dielectric material; and, forming a layer of superconducting material on the layer of nonlinear dielectric material.
13. The method of claim 12 wherein said nonlinear dielectric material is selected from the group consisting of strontium titanium oxide, barium strontium titanium oxide and barium titanium oxide and said superconducting material is yttrium barium copper oxide.
